BED FRAME

Richard A. Nowell, Los Angeles, Calif., assignor,
by mesne assignments, to Metalcraft Co., Los
Angeles, Calif., a copartnership

Application April 3, 1950, Serial No. 153,561

17 Claims. (Cl. 5—285)

1

This invention relates to a bed frame and more particularly pertains to a bed frame of the knock-down or collapsible type comprising side rails and end rails formed of metal bars.

An object of the invention is to provide a bed frame of the above character which is adapted to be easily and quickly assembled and disassembled and when disassembled may be arranged into a compact package which will occupy but little space in storage or shipment and which may be readily handled and transported.

A particular object of the invention is to provide a construction in a bed frame whereby the ordinary bed-caster assembly may be utilized as a means for effecting an interlocking connection between the side rails and end rails of the bed frame to hold the frame in its assembled position and to equip the frame with caster supports and whereby on removing the casters the bed frame may be readily disassembled.

With the foregoing objects in view, together with such other objects and advantages as may subsequently appear, the invention resides in the parts and in the combination, construction and arrangement of parts hereinafter described and claimed, and illustrated by way of example in the accompanying drawing, in which:

Fig. 1 is a perspective view of the bed frame in its assembled position.

Fig. 2 is a view in cross section and elevation as seen on the line 2—2 of Fig. 1.

Fig. 3 is a detail in horizontal section taken on the line 3—3 of Fig. 2.

Fig. 4 is a detail in horizontal section taken on the line 4—4 of Fig. 2.

Fig. 5 is a view in elevation of a side rail of the bed frame as seen from the inner side thereof.

Fig. 6 is an enlarged section taken on the line 6—6 of Fig. 5.

Fig. 7 is a view in elevation of one of the end rails of the bed frame.

Fig. 8 is an enlarged section and elevation as seen on the line 8—8 of Fig. 7.

Fig. 9 is an elevational view of a conventional caster wheel assembly employed as a connector between the side and end rails of the bed frame.

Figs. 10, 11, 12 and 13 are perspective views of inverted fragmentary portions of a side and end rail depicting the manner of effecting their assemblage.

Fig. 14 is a detail in section taken on the line 14—14 of Fig. 2.

Fig. 15 is a plan view of a foldable bed frame to which a feature of the invention is applicable, showing the frame in a partly collapsed position.

2

Fig. 16 is a plan view of one end portion of the bed frame shown in Fig. 15 in its extended position.

Fig. 17 is a view in section and elevation taken on the line 17—17 of Fig. 16.

Fig. 18 is an enlarged section and elevation as seen on the line 18—18 of Fig. 16, and

Fig. 19 is a perspective view of an end portion of a side and end rail showing the parts inverted and in a folded or disassembled position.

Referring to the drawings more specifically, reference now being had to Figures 1 to 14 thereof, A—A indicate a pair of side rails and B—B designate a pair of end rails of a bed frame, 15 which rails are formed of metallic bars here shown as of L-cross section.

The side rails A—A are each provided adjacent the ends thereof with metal brackets C—C which are securely fixed to the rails to 20 depend therefrom. As here shown each of the brackets C embodies a flat web 20 formed at opposed inner and outer ends thereof with in-turned flanges 21 and 22. The inner flange 21 abuts the underside of the side rail A and is 25 fastened thereto in conventional fashion with the web 20 extending parallel with the side rail adjacent to the outer margin thereof. The outer flange 22 serves as a portion of a connection for an end of one of the end rails B, and is formed

20 with an aperture 23 to receive the tubular socket member 24 of a conventional caster D which is also engageable with the end portion of the end rail B supported above the flange 22 as will be later described.

30 The web 20 of each of the brackets C is fitted with a pair of headed studs 25 and 26 which project from the inner face of the web medially of the side margins thereof; the studs 25 and 26 being spaced apart and aligned perpendicular to the flanges 21 and 22 with the upper stud 25 spaced from the flange 21 and the lower stud 26 spaced from the flange 22. The studs 25 and 26 serve as a means for detachable interlocking engagement with the end of the end rail B; the stud 26 affording a supporting connection between the bracket C and the rail end.

35 Each of the end rails B is formed with upturned end portions 27 and 28 embodying a flange 29 formed at the upper end thereof with a notch 30 engageable with one of the studs 25 and 26 formed on a margin thereof intermediate its ends with a notch 31 engageable with the companion stud 26. Each end portion of each end rail B is formed adjacent the base of the flange 29 with an aperture 32 arranged to register with

50

the aperture 23 in the flange 22 when the end of the rail B is positioned above the latter; the aperture 32 being adapted to receive the socket member 24 of the caster D as particularly shown in Fig. 14.

In assembling the bed frame the side rails A—A are arranged in suitable spaced parallel relation to each other in an inverted position, whereupon the end rails are connected thereto in the manner illustrated in Figs. 10 to 13 inclusive; 10 the end rail B being initially positioned with the end portions thereof laying sideways upon the then upwardly presented flange 21, as shown in Fig. 10, with the notch 30 on the end of the flange 29 presented to the stud 25 and 15 with the notch 31 in the flange 29 extended upwardly. The end rail B is then advanced on the flange 21 in the direction indicated by the arrow a in Fig. 10, to bring the end notch 30 into engagement with the stud 25, whereupon, 20 utilizing the stud 25 as a pivot, the end rail is swung upwardly in the direction indicated by the arrow b in Fig. 11 to advance the side notch 31 in the flange 29 into engagement with the stud 26 as shown in Fig. 12. The apertures 32 in the 25 end portion of the end rail B will then be disposed in register with the apertures 23 in the flanges 22 whereupon the socket members 24 of the casters D are inserted through the apertures 23 and 32 as indicated in Figs. 12 and 13 thus 30 locking the ends of the end rail B in engagement with the flange 22 which, with the interlocking engagement afforded by the headed studs 25 and 26 with the flanges 29, effects a strong 35 and substantial interconnection between the ends of the end rail B—B and the side rails A—A through the brackets C.

In order that the connection between the ends of the end rail B—B and the bracket C be such as to obviate lost motion in the connection, the 40 heads of the studs 25 and 26 have their inner faces spaced from the contiguous faces of the web 20 a distance corresponding to the thickness of the flange 29 and are adapted to overlie the margins of the notches 30 and 31 so as to clamp 45 the outer faces of the flanges 29 tightly against the webs 20 of the brackets C. Likewise the apertures 23 and 32 are dimensioned to effect a snug fit with the socket member 24 of the caster D such as to prevent lost motion in this 50 connection and at the same time afford gripping engagement with the member 24 so as to hold the caster in place on inverting the bed frame and disposing it in its normal upright position as shown in Figs. 1 and 2. When the assembled 55 bed frame is restored to its upright position the end rail B—B will be supported on the side rails A—A by the studs 26 on the brackets C and will be securely fastened against displacement by the engagement between the end rail and the 60 caster socket members.

Manifestly when the bed frame is disassembled the side rails A—A and end rails B—B with the several casters D may be assembled in a compact package as by wiring them together in a bundle.

Referring now to the construction shown in Figs. 15 to 18 illustrating the application of the employment of the locking feature of the casters in a collapsible bed frame structure, E—E represents the side rails of the bed frame which are connected together by collapsible end rails F—F which latter comprise foldable end members 35 and 36 having their outer ends connected by pivots 37 to the side rails E—E at points spaced in 70

wardly from the ends of the latter, and having their outer ends adapted to be disposed in an overlapping extended position and connected together as by bolts and wing nut assemblies 38 carried by the members 35 engaging the members 36 through keyhole slots 39 in the latter in conventional fashion. Mounted on each of the foldable members 35—36 of the end rails F to project downwardly therefrom is a tube 40 having a bore 41 therein constituting an aperture adapted to receive and snugly conform to the socket member 24 of a caster D.

Pivoted mounted on the outer end portions of the side rails E by pivot pins 42 are inclined brackets G the outer end portions of which are adapted to overlie the outer ends of the tube 40 when the end rails F are disposed in their extended position as shown in Figs. 16 and 17. The brackets G will then extend inwardly and downwardly in diagonal relation to the side rails E—E. Apertures 43 are formed in the outer end portions of the brackets G to register with the apertures 41 in the tube 40, so that socket members 24 of the casters may be passed through the aperture 43 and extend into the aperture 41 to effect interconnection between the bracket G and the tube 40 thereby locking the foldable end rails F in their extended positions.

When it is desired to collapse the bed frame just described the casters D are removed whereupon the end rails F may be folded to overlie the side rails E together with the brackets G which may likewise be swung on the pivots 42 to extend parallel with the side rails E as shown in Fig. 19.

While I have shown and described a specific embodiment of my invention, I do not limit myself to the exact details of construction set forth, and the invention embraces such changes, modifications and equivalents of the parts and their formation and arrangement as come within the purview of the appended claims.

1. In a bed frame, side rails, depending brackets fixed on said side rails, end flanges on said brackets each having a caster receiving apertures therein, end rails supported by said brackets and having end portions overlying said end flanges and formed with apertures disposed to register with the bracket apertures when the end rails are positioned with their end portions overlying the end flanges, and casters having socket members removably inserted in the registering apertures to connect the end rails to the side rails.

2. The structure called for in claim 1 together with headed studs on said brackets and end flanges on said end rails having notches engaged with said headed studs in connecting said end rails and side rails when forming a bed frame.

3. A bed frame comprising a pair of side rails, a depending bracket on and adjacent each end of said side rails and having an inturned flange on the lower end thereof formed with a caster receiving aperture, a pair of vertically spaced headed studs on the inner face of each of said brackets spaced above said flange, a pair of end rails having end portions formed with apertures, said end rails being arranged longitudinally between said side rails with the apertures therein in registering with the apertures in certain of said flanges, casters having socket members removably engaged with the registered apertures in said flanges and end rails to detachably fasten the end rails to said flanges, and end flanges on

said end rails formed with notches engaging the headed studs on the brackets.

4. In a bed frame, a side rail, a depending bracket carried on said rail having an inturned lower end portion formed with an aperture adapted to receive a caster, a headed stud on said bracket projecting over said apertured end portion and spaced therefrom, an end rail having an end flange formed with a notch engaged with said stud and formed with an aperture adjacent to the base of said flange registering with the aperture in said bracket when said notch and stud are engaged, and a caster having a socket member engaged with said apertures to hold the notch and stud in interengagement.

5. In a bed frame, a side rail, a depending bracket embodying a web and parallel end flanges having one of said end flanges affixed to the underside of said side rail, the other of said end flanges being formed with a caster receiving aperture, a headed stud projecting from said web between said end flanges, an end rail having an end portion adjacent said apertured end flange formed with an aperture registering with the end flange aperture and having a notch slidably engaged with said headed stud, and a caster having a socket member removably inserted in said registering apertures.

6. In a bed frame, a side rail, a depending bracket thereon having an inturned lower flange formed with a caster receiving aperture, a headed stud projecting from said bracket above said flange, an end rail having an end portion, an end flange on said end portion of said end rail formed with a notch in the outer end thereof slidably engaged with said headed stud to form a pivotal connection between said bracket and end flange on which said end rail is turnable to position the end portion of the end rail over the aperture in the lower flange of the bracket; said end portion of the end rail being formed with an aperture arranged in registry with the first named aperture, and a caster having a socket member inserted in the registered apertures.

7. In a bed frame, a pair of side rails, a depending bracket mounted adjacent each end of each of said side rails, a pair of end rails shiftably supported by opposed ones of said brackets and adapted to be so arranged relative to said side rails as to cooperate therewith to form a bed frame, and a caster socket member detachably connecting each end of each of said end rails to certain of said brackets, said brackets and end rails having alignable communicating seats receiving said caster socket members.

8. A bed frame comprising a pair of spaced parallel side rails, a depending bracket on each end portion of each of said side rails, a lower end flange on each of said brackets having a caster receiving aperture therein, a caster socket member snugly but removably received in the aperture of each of said flanges, and a pair of end rails extending longitudinally between the end portions of the side rails, and said end rails detachably connected at each end thereof to one of the socket members.

9. A bed frame comprising a pair of spaced parallel side rails, a pair of end rails, means shiftably connecting the end rails to the side rails to form a bed frame; the end rails having opposed end portions each of which is arranged adjacent one of the side rails, and each of which is formed with a caster receiving opening, a bracket on and adjacent to each end of each

of said side rails arranged for cooperation with an adjacent end of one of the end rails, a flange on each of said brackets formed with a caster receiving aperture, the ends of said end rails being disposed with the apertures therein in register with the apertures in flanges of opposed brackets on the pair of side rails when the side and end rails are in their bed frame forming position, and a series of casters each having a socket member; there being a caster for each end of each of said end rails arranged with its socket member inserted in the aperture in the end portion of the end rails and in the aperture registered therewith of the adjacent flange to connect the side rails and end rails together against shifting.

10. The structure called for in claim 11 and wherein the means shiftably connecting the end rails to the side rails comprising headed studs on said brackets and end flanges on said end rails having notches engaged with said headed studs; said caster socket members releasably locking the end flanges of said end rails in engagement with said headed studs.

11. In a knock down bed frame, a pair of side rails and a pair of end rails, said end rails being adapted to be so arranged with respect to the side rails as to cooperate therewith to form a bed frame, means carried by one pair of rails and shiftably supporting the other pair, said side rails and said end rails each having an aperture adjacent each end thereof; the apertures on the side rails being disposed to register with the apertures on the end rails when the rails are arranged to form a rectangular bed frame to form cooperating casters receiving apertures at each corner of the frame, and a caster having a bearing shank portion removably positionable in said cooperating apertures.

12. A knock down bed frame comprising a pair of side rails, a pair of end rails for assemblage with the pair of side rails to form a bed frame, a pair of depending brackets mounted on each of said side rails with one of the brackets of a pair thereof disposed adjacent one end of a side rail and the other bracket of the pair disposed adjacent the other end thereof with the pair of brackets on one of the side rails arranged to oppose the pair of brackets on the other side rail when said side rails are positioned in spaced parallel relation for assemblage in a bed frame, an end flange on each of said brackets formed with an aperture, a pair of headed studs on each of said brackets extending over said flange in spaced relation thereto and to each other, an upstanding end flange on each end of each of said end rails having side notches detachably engaging with the pair of headed studs on one of said brackets in assembling the bed frame, each of said end rails having an aperture formed adjacent each end thereof arranged to register with the aperture in the flange of a bracket with which an end flange of the end rails is engaged when assembling the bed frame for the reception of a caster socket member when an end of an end rail is connected to an end of a side rail, and a caster having a bearing shank portion removably positionable in said registering apertures.

13. In a bed frame, a pair of side rails, a pair of end rails so arranged with respect to the side rails as to cooperate therewith to form a bed frame, said end rails being formed adjacent each end thereof with an aperture, depending brackets on the side rails for connection with the ends of the end rails, means for detachably connecting

the ends of the end rails to said brackets; said brackets each having a horizontal member formed with an aperture with which an aperture at one end of an end rail registers in superimposed relation when such end is connected to the bracket, and a castor socket member also connecting the ends of the end rails to the brackets with which they are connected; said socket members being received in the registered apertures.

14. In a bed frame including side rails and end rails for arrangement relative to each other to form a bed frame; brackets on the side rails, each bracket having an aperture therein, a castor member removably insertable in the aperture of each of said brackets; said end rails each having an aperture adjacent each end thereof arranged to register with a bracket aperture and to receive the castor member when inserted in the latter.

15. In a bed frame including separable side rails and end rails for arrangement relative to each other to form a bed frame; brackets on said side rails each having a lower end portion formed with an aperture; each end portion of the end rails having an aperture in register with an aperture in a bracket end portion when the side and end rails are in their bed frame forming position, and casters detachably connecting the ends of the end rails to said brackets; said casters each embodying a socket member removably inserted in

8
registered apertures of one end portion of an end rail and of one of the brackets to lock the side and end rails together.

16. In a bed frame, a side rail, an end rail, a depending bracket on said side rail having a castor member receiving aperture, said end rail having a castor member engaging means positioned to align with the bracket aperture, a castor member engageable with said aperture and engaging means to connect said rails together, and end rail sustaining means at least in part carried by said bracket.

17. In a bed frame, a side rail, an end rail, a depending bracket on one of said rails having a castor member receiving aperture, the other rail having a castor member engaging means aligned with said aperture, a castor member extending through said aperture into engagement with said engaging means connecting said rails together, and supporting means for said second rail at least in part provided by said bracket.
